Patented July 27, 1965

201,776

HANG UP SOAP BAR OR SIMILAR ARTICLE

Gordon K. Woodard, 14155 Magnolia Blvd., Apt. 354,
Van Nuys, Calif.

Filed June 1, 1964, Ser. No. 80,213

Term of patent 14 years

(Cl. D73—1)

FIG. 3

FIG. 1

FIG. 2

FIGURE 1 is a perspective view of a hang up soap bar or similar article showing my new design;

I claim:

The ornamental design for a hang up soap bar or similar article, substantially as shown.
